UNITED STATES PATENT OFFICE.

GEORGE E. WITHERELL, OF HARTFORD, CONNECTICUT, ASSIGNOR TO
REMINGTON ARMS COMPANY, OF ILION, NEW YORK, A CORPORA-
TION OF NEW YORK.

SINGLE-TRIGGER MECHANISM FOR FIREARMS.

No. 808,890.

Specification of Letters Patent.

Patented Jan. 2, 1906.

Application filed May 23, 1902. Serial No. 103,662.

To all whom it may concern:

Be it known that I, GEORGE E. WITHERELL, a citizen of the United States, and a resident of Hartford, in the county of Hartford and State of Connecticut, have invented certain new and useful Improvements in Firing Mechanism for Firearms, of which the following is a specification.

My invention relates to that class of firearms in which a plural number of barrels, of hammers, and of sears are employed and in which there is mechanism by means of which a plural number of sears may be operated from a single trigger; and the object of my invention is to provide means for determining the order in which the several barrels shall be discharged or for enabling any predetermined barrel to be discharged at will. A device by means of which these objects may be attained is illustrated in the accompanying drawings, in which—

Figure 1 is a plan view of the rear portion of the barrels and of a part of the stock of a gun with parts broken away to show construction, the gun being "broken down." Fig. 2 is a view in side elevation of the same with parts broken away to show construction. Fig. 3 is a detail diagram view showing in plan the hammers, sears, and interceptor-slide, the right-hand barrel having been discharged. Fig. 4 is a like view, but showing the position of the parts at the instant following the discharge of the right-hand barrel and during the counter-recoil. Fig. 5 is a detail view in side elevation, showing the relative position of the parts shown in Figs. 3 and 4 and after the discharge of a barrel. Fig. 6 is a detail view showing in plan the trigger and the rear end of the sears and couplers. Fig. 7 is a detail side view of the same.

The invention is shown and described herein in connection with a shotgun having a single trigger; but it is obvious that the invention may be applied to other forms of firearms and those in which a plural number of triggers may be employed, and I do not limit myself to the application of the invention in the specific form of gun herein shown, which has been chosen merely as a convenient form in which the invention may be embodied.

In the accompanying drawings the numeral 1 denotes the barrels, 2 the stock, 3 the frame, and 4 the fore-end, of the gun. There are also

provided cocking-levers 5 and hammers 6, these parts being of ordinary and well-known form and mounted in the ordinary manner in guns of this class, except as to parts of the hammer, and a more detailed description is deemed unnecessary. It is to be understood, however, that in this specification a description applying to a set of parts applicable to a single barrel will apply equally well and is to be considered as applying to a set of devices applicable to another barrel of the same piece.

The hammer 6 is provided with a notch 7, into which the sear 8 engages for the purpose of holding the hammer in its raised or cocked position, and the hammer also has a cam projection 9 for a purpose to be hereinafter described.

A sear 8 is mounted appurtenant to each of the hammers, and the rear end or sear-tail is overturned at 10, forming a recess within which a nose 12 on a coupler 11 projects. The couplers 11 are pivotally mounted on the sears 8, and each is provided with a stop-pin 13, which takes against the side of the overturned portion 10 of the sear and limits the inward movement of the coupler on which it is borne, the nose being located in said recess. The edges of the noses 12 on the couplers are beveled on their ends and sides and are located opposite each other, each being adapted to engage with the recess in the opposite sear without respect to the position of the sear-tail with which the nose is to engage. A cam 14 is mounted on each of the couplers, which cooperates with the cam projection 9 on the hammer when these two parts are engaged, the coupler being located with the nose in its backward position. Coupler-springs 15, secured to the sears, press against the couplers and hold them normally with their noses at the inner limit of their play.

A trigger 17 is mounted on the trigger-plate 16, underlying the sear-tails. This trigger is pivoted in a manner common to this class of guns and operates the sears by a backward pull on the trigger, which raises that part adapted to engage the sear. A trip 18 is pivotally mounted on the trigger in such position that its forward end may engage with either of the sear-tails, the main part of the trigger being located so far below the sear-tails that in the movement of the trigger such main part will not encounter either sear-tail.

This trip is secured to a trip-pin 19, which projects through the trigger and to the opposite end of which is secured a trip-lever 20. It will be noted that by manipulating this 5 trip-lever 20 the trip 18 may be located in position to engage the sear-tail of either sear, but is adapted to engage only one of said sears in each movement of the trigger.

An interceptor-slide 21 is mounted on the trigger-plate 16 in any preferred manner. In the form shown guideways 22 are formed in the sides of the safety-stud 23, the interceptor-slide straddling said stud, and projections on the forward end of the slide engage grooves 5 in the sides of the tang-stud 24. This interceptor-slide is enlarged at its rear end, and a guide-pin 25 projects into this enlarged end and forms a guide for the interceptor-slide, a spring 26 on said guide-pin holding the interceptor-slide at the forward limit of its play. An interceptor 27 is located at the front end of the interceptor-slide and has an upward extension arranged to be interposed between the noses 12 of the couplers 11 at certain periods, as at the instant after the discharge of the barrel and during the counter-recoil. The object of this is to prevent the premature discharge of the barrel immediately following the initial discharge in a double-barrel gun. The interceptor-slide is of considerable weight and its inertia is not quickly overcome. When the piece is fired, all of the parts, including the interceptor, move backward, as the stud 24 of course makes it imperative that the part 21 and connected parts move backward under the influence of the discharge. Instantly the counter-recoil takes place and all parts of the gun move forward with the exception of the interceptor, which being loosely mounted with reference to other parts remains quiescent for an instant, and this brings the interceptor between the noses of the couplers and prevents said couplers from operating during the counter-recoil and when pressure is necessarily though involuntarily brought to bear on the trigger. The light spring 25 normally holds the interceptor and appurtenant parts in a forward position and also aids in quickening the movement of said interceptor after it has performed its function in preventing the operation of the coupler. Of course the interceptor only rests in an intercepting position practically for an instant, just when the counter-recoil would cause an involuntary pull on the trigger. The light spring quickens its action, and after it has performed its function it immediately moves into a normal position ready to act again. A further object of the spring is to permit the use of the gun in any position—as, for instance, straight over the shoulder.

The operation of the device is as follows: The gun is loaded in the usual manner by breaking down the barrels, inserting the cartridges, and swinging the barrels back to place

and locking them. This operation cocks the piece, the hammers being now in the position shown in Fig. 2. It may now be determined which barrel is to be fired first by swinging the trip-lever 20 to the right or left, according to which barrel is to be fired first—that is, if the right-hand barrel is to be fired first the trip-lever 20 is swung to the right side of the trigger 17. This operation places the trip 18 in position to engage the sear appurtenant to the right-hand barrel, and the trigger being pulled the hammer 6 appurtenant to the right-hand barrel is released and causes the discharge of that barrel. As the hammer descends the cam on the forward end of the 80 coupler 11 rides down the projection 9 of the hammer under the force exerted by the coupler-spring 15, and the nose 12 of the coupler appurtenant to the right-hand barrel engages within the recess in the sear appurtenant to the 85 left-hand barrel. During the operation of the firearm in discharging the right-hand barrel, however, and before the coupler has assumed the position engaging the recess in the left-hand sear, as above described, the forward 90 movement of the gun caused by the counter-recoil has been so sudden that the interceptor-slide remains in its rearward position—that is, the gun is forced forward independent of the interceptor-slide. This causes the interceptor 27 to be located temporarily in the path of movement of the couplers and prevents their operation at that instant, so that for the instant the sears are not locked together. This operation of the interceptor-slide prevents a premature discharge of the left-hand barrel immediately following that of the right-hand barrel by any pressure that may be brought to bear on the trigger by the finger in the counter-recoil of the gun. The coupler having operated to connect the two sears, as above described, a second pull on the trigger will raise the right-hand sear and, through the medium of the coupler, the left-hand sear also, thus releasing the hammer appurtenant to the 100 left-hand barrel, which is thereby discharged. 105

A detent 28 is located in a recess in the trigger, with its outer end normally engaging notches in the trip 18. There are preferably two of these notches, as shown in Fig. 6 of the drawings, and the detent is held normally in engagement with the notches by force exerted by a spiral spring 29. This serves to maintain the trip in either of the two positions, so that a pull on the trigger may operate either of the two sears. 115

What I claim as my invention, and desire to secure by Letters Patent, is—

1. In a multibarrel firearm having a plural number of hammers and a plural number of sears and their appurtenant parts, a coupler mounted on each of the sears and adapted to engage and operate the opposite sear, a trigger, and a connection between the trigger and sears adapted to initially engage either sear 125 130

and subsequently operate the other sear without changing its position.

2. In a multibarrel firearm having a plural number of hammers and a plural number of 5 sears and their appurtenant parts, a coupler mounted on each of the sears and adapted to engage and operate the opposite sear, said couplers controlled by the hammers, a trigger and a connection between the trigger and 10 sears adapted to initially engage either sear and subsequently operate the other sear without changing its position.

3. In combination, in a firearm having a plurality of barrels, hammers, sears, and appurtenant parts, a trigger for actuating said sears, provided at its upper and under sides with recesses, a thumb-lever projecting into the lower recess and a sear-actuating lever projecting into the upper recess, said levers rigidly connected by a pin passing through the trigger adjacent to the recesses and a spring-detent appurtenant to the upper recess adapted to hold the parts in positive position of adjustment.

25 4. In a multibarrel firearm having a plural number of hammers and a plural number of sears and their appurtenant parts, a trigger, means intermediate the sears and trigger for automatically operating one of said sears after 30 the operation of the other of said sears, a connection mounted on the trigger adapted to initially operate either of said sears and means for temporarily preventing the action of the automatic sear-operating means.

35 5. In a multibarrel firearm having a plural number of hammers and a plural number of sears and their appurtenant parts, automatic connections intermediate the sears whereby one of said sears may be operated after the 40 other of said sears, a trigger for operating both of said sears, a connection mounted on the trigger and adapted to initially operate either of said sears, and elastically-controlled means for preventing the operation of the 45 automatic sear-actuating means.

6. In a multibarrel firearm having a plural number of hammers and a plural number of sears and their appurtenant parts, a trigger for actuating said sears, a connection mounted 50 on the trigger and coöperating with the trigger to initially operate either of said sears, an automatic connector adapted to couple said sears after either has been moved, and elastically-controlled means for temporarily preventing 55 operative movement of the trigger and its connection.

7. In a multibarrel firearm having a plural number of hammers and a plural number of sears and their appurtenant parts, a coupler

mounted on one of said sears and adapted to 60 engage the opposite sear, a trigger, a connection coöperating with the trigger and adapted to initially operate either of the sears and subsequently operate the other sear without changing its position, an elastically-controlled 65 means for temporarily preventing a sear-actuating movement of the trigger and connection.

8. In a multibarrel firearm having a plural number of hammers and a plural number of 70 sears and their appurtenant parts, a coupler located on one of the sears and adapted automatically to engage the opposite sear, a trigger, a connection mounted on the trigger and adapted to initially operate either sear, means 75 for moving said connection and elastically-retracted means for temporarily preventing the automatic action of said coupler.

9. In a multibarrel firearm having a plural number of hammers and a plural number of 80 sears and their appurtenant parts, a coupler mounted on one of the sears and adapted automatically to engage the opposite sear, a trigger, a connection mounted on the trigger and adapted to initially connect the trigger with 85 either sear, means located outside of the piece for moving said connection, and elastically-retracted means for temporarily preventing the automatic action of the coupler.

10. In a multibarrel firearm having a plural 90 number of hammers and a plural number of sears and their appurtenant parts, a coupler mounted on one of the sears and adapted automatically to engage the opposite sear, a trigger, a connection mounted on the trigger and 95 adapted to initially operate either sear, means located on the trigger for moving said connection, and elastically-retracted means for temporarily preventing the automatic action of the coupler.

100 11. In a firearm having a plural number of barrels, hammers and sears with their appurtenant parts, a trigger, a shifting trip borne on the trigger and pivoted at one end and with its other end lying below the sears, the pivot 105 secured to said trip and extending into the trigger, a lever having one end secured to the pivot and its opposite end extending in the same direction as the sear end of the trip whereby the trip and lever have identical 110 movements and means for resiliently holding said trip and lever in their various positions of adjustment.
